Filed Mar. 11, 1964, Ser. No. 78,962

Term of patent 14 years

(Cl. D26—14)

FIG. 1.

FIG. 2.

FIG. 1 is a perspective front view of the magnetic tape recorder embodying the design, wherein the pivotable cover is closed;

FIG. 2 is a perspective rear view of the tape recorder shown in FIG. 1; and

FIG. 3 is a similar view to FIG. 1 wherein, however, the cover is shown in its open position.

The bottom, not shown, is a flat unornamented surface. The portion of the handle not shown is continuous between the portions shown.

I claim:

The ornamental design for a magnetic tape recorder, substantially as shown and described.
